UNITED STATES PATENT OFFICE.

THOMAS H. STRALEY, OF PHILADELPHIA, PENNSYLVANIA, ASSIGNOR TO STANDARD ELEVATOR INTERLOCK COMPANY, OF PHILADELPHIA, PENNSYLVANIA, A CORPORATION OF PENNSYLVANIA.

INTERLOCK MECHANISM FOR ELEVATORS.

Application filed March 21, 1921. Serial No. 454,009.

To all whom it may concern:

Be it known that I, THOMAS H. STRALEY, a citizen of the United States of America, residing in Philadelphia, in the county of 5 Philadelphia and State of Pennsylvania, have invented a new and useful Improvement in Interlock Mechanism for Elevators, of which the following is a specification.

The object of the invention is to construct 10 an interlock mechanism for use in elevators operated by different kinds of motor and control mechanisms; the interlock mechanism being so designed and constructed as to prevent opening of the enclosure doors 15 at the floor landings until the car is at the desired landing, and the car control mechanism is in its stop or "off" position. When the car is at rest at a landing, and the enclosure door unlocked, and open, the interlock mechanism also renders it impossible 20 to operate the car control mechanism. Conversely, it also prevents the operator of the car from starting his car until the enclosure door has been moved to its closed position, 25 and securely locked.

The present interlock mechanism is easily and readily attached to the well structure at the landings and connected to the enclosure doors and car control mechanism, 30 and does not alter the appearance of the elevator in any way.

Furthermore, in case the interlock mechanism at any of the landings is damaged, it does not interfere with the operation of 35 the interlock mechanism at the other landings nor with the normal operation of the car.

It is adapted to be used with either hydraulic or electric elevators; switch control mechanism generally, with horizontally 40 sliding enclosure doors, operable either from the right or left hand; vertically sliding up-and-down doors; car lever control mechanism with foot button operation of the interlock mechanism; car hand wheel control mechanism, with foot button operation of 45 the interlock mechanism; and car hand rope control mechanism, with foot button operation of the interlock mechanism.

Various other objects and adaptations of 50 the interlock mechanism to be used with elevators will more fully appear as herein-after disclosed.

I attain these objects by the mechanism

described in the specification, and pointed 55 out in the claims, and illustrated in the accompanying drawings, in which—

Figure 1 is a view in elevation of the interlock mechanism, looking at its front side as it appears in the figure, its parts being 60 in the position they assume when the mechanism is unlocked, and the enclosure or hatchway door is fully opened.

Figure 2 is a front view, with the parts 65 in the position they assume when the mechanism is locked, and the door fully closed.

Figure 3 is a view in elevation, taken on the dotted line 3—3 in Figure 1, looking in the direction the arrows are pointed.

Figure 4 is a view in elevation of a 70 bracket, adapted to be fastened to the bottom of the car, a link, a fork, a roller, and a coupling to connect the link to the car control mechanism, and for other purposes hereinafter described.

Figure 5 is a view in elevation of the interlock mechanism, looking at its front, and assembled with the parts mentioned in Figure 4.

Figure 6 is an end view in elevation of 80 Figure 5, but without showing the bracket.

Figure 7 is a view in horizontal section, taken through the interlock mechanism, Figure 5, on line 7—7.

Figure 8 is a view in horizontal section, 85 taken through the interlock mechanism, with the mechanism locked by its latch engaged with the channel piece.

Figure 9 is a general arrangement view in elevation of the interlock mechanism, looking at its end as it appears on the figure, applied to a horizontally sliding door, with car switch lever control mechanism unlocked.

Figure 10 is a view in elevation of the 90 front side of the interlock mechanism, as it appears in the figure, applied to a horizontally sliding door, closed, and the interlock and car control mechanism locked, and unlocked respectively.

Figures 11 and 12 are views similar to those of Figures 9 and 10, except that the door is vertically sliding, and the part on the door which connects the latter is shown as a bent bar instead of a straight bar, and the lever as a bell-crank instead of a straight lever.

Figures 13 and 14 are views similar to

Figures 11 and 12, except that the door is shown as divided horizontally into two parts, and which are slideable vertically up-and-down to open and close.

5 Figures 15 and 16 are general assembly front and end views, with hand lever car control mechanism, and foot button operation.

10 Figures 17 and 18 are general assembly views with hand wheel car control mechanism, and a foot button operation, and means to lock the hand wheel.

15 Figures 19 and 20 are general assembly views with hand rope car control, and foot button operation, and a vertically sliding door.

Similar numerals refer to similar parts throughout the several views.

The parts constituting the invention may 20 be secured immediately to the floor landing; but for convenience they are mounted on a base plate, 1, having at its left hand edge, looking at its front face, as it appears in the figures of the drawings, two vertically 25 perforated lugs, 2, spaced apart from each other, and between which is mounted a vertically perforated knuckle, 3, of a latch bar, 4 on a pin, 5. The latch bar in its normal position lays across the front face 30 of and against the base plate, with the ends of the knuckle spaced apart from the lugs, to allow the knuckle to move up and down on the pin, as well as turn thereon, both to swing and move up and down on the pin, 35 from its normal or retracted position to its extended position and vice versa, as will be referred to again later on. Projected from the front face of the base plate, at one side of the knuckle, are two additional lugs, 6, 40 spaced apart from each other, and between which the latch bar is designed to lay in its normal or retracted position. The opposing faces of the lugs, 6, are inclined or beveled outwardly. As the base plate is intended 45 to be affixed to the floor landing with the knuckle, 3, in substantially a vertical position, gravitational force will tend to cause the knuckle to slide down on its pin, 5, until it is arrested by the lug, 2, beneath it and 50 the bar, 4, will likewise tend to fall down, and as the inclined face of the lug, 6, is beneath it, and in its path, the bevel will guide the bar outwardly to an extended position, and conversely, when the bar is in that 55 position, and is thereupon pressed inwardly in the direction towards the base plate to its retracted position, it will, in such inward movement, be guided upwardly as well in consequence of its contact with the bevel 60 face of the lug, and the knuckle be restored to its position away from the lug, 2. As the interlock mechanism is designed to be used with doors which open either from the right hand or the left hand, and to invert the base 65 plate to meet that condition, two lugs, 6,

are provided; it is evident that each lug will function substantially alike; so it is deemed unnecessary to describe the operation of the latch bar and knuckle in connection with both of the lugs, 6; the description of one 70 being enough to cover both of them. At one side of and in a line drawn between them, is a short stud, 7, on the base plate, adapted to hold a coiled expansion spring, 8. In the latch bar, on its under side, and 75 opposite the stud, is a recess, 9, adapted to receive the stud and spring, and also allow the latter to extend against the latch bar, to tend to swing the latter outwardly away from its contact with the base plate to an extended position, and retain it there against being accidentally returned to its retracted position. The force of the spring is merely 80 accessory to gravitational force, to make assurance doubly sure that the latch bar will be extended. It may be found to be preferable to use the spring, but it is plain that it is designed that gravitational force alone shall be sufficient. In the base plate, 85 underneath the free end of the latch bar, 90 is a depression, 10, with its bottom on a slant in the direction of the free end of the bar, adapted to receive the bar in its retracted position against the plate. Along what are called the top and bottom edges 95 of the base plate, are horizontally-placed open slots, 11. In the slots, shoes, 12, are guided, to which are secured flat slide pieces, 13, which are held to the base plate by the overhanging heads of bolts, 14, let 100 into the base plate. Between the edge of the same and the free end of the flat slide pieces, are tension springs, 15, which serve to tend to move the flat pieces toward the left hand and the middle line of the plate, 105 and retain the flat pieces in that central position. The other end of the flat pieces is secured to the upstanding side, 16, next to the base plate, of a channel piece, 17, 110 the other side, 18, of which is virtually parallel with the front face of the base plate. In the edge of the side, 16, is a notch, 19, in line with the free end of the latch bar, and of sufficient dimensions to 115 allow it to protrude through the notch when the side, 16, and the channel piece are moved across the front face of the plate towards its middle position thereon or towards the knuckle of the bar, in which 120 position the free end of the latch bar is in the notch, 19, in the side, 16, of the channel piece, 17. In the angle or joint between the sides, 16, and 18, immediately over the notch, and in line with the latch bar, 125 is a triangular shaped block, 20, with its base line or outer face rounded, more or less, which block is designed to be engaged by the end of the bar when the latter is in its extended position. The rounding of the 130 base line of the block is merely to facilitate

the engagement between the block and bar. It will be perceived that, if and when the channel piece is moved from over the end of the latch bar, that gravitational force 5 will cause the knuckle of the bar to fall down on the pin, 5, and the bevel face of the lug, 6, will direct the bar in its falling movement outwardly or away from the base plate, or, if for any adventitious reason, 10 gravitational force is not sufficient to cause the said movement of the bar, the spring, 8, will add its force to move the bar away from the plate. At the instant the free end of the bar becomes free of the notch, 19, 15 its end will bear against that portion of the side, 16, immediately over the notch, and between the latter and the block, 20. If the movement of the channel piece be arrested at that time, it will be locked 20 against an opposite or reversal movement by the fact of the engagement between the abutting end of the latch bar against the side, 16, of the channel piece. That position 25 of the channel piece and bar may be assumed to represent the condition of the interlock mechanism when the hatchway door is not closed over the entire opening of the hatchway door opening; but, instead, is only partially closed over the opening, 30 In the use of interlock mechanisms, it is sometimes the practice not to arrange to close the door entirely across the opening, but only to close it part way, thereby leaving an open space between the door and 35 the jamb, but not sufficiently wide to allow a person to thrust through the open space. It may be explained that such practice is based on the consideration that the use of an interlock mechanism may tend to slow 40 up the operation of the elevator in service conditions, since the door must be in a closed position before the car may be started away from the landing and the latter must be at the landing before the door can be 45 opened, which means in effect that the time taken to open and close the door must be added to the running time of the elevator. By having the closed and locked position 50 of the door to correspond to a partially closed position, say, two, three or four inches from the door jamb, the distance which the door will have to be moved to a fully closed or opened position will be accordingly less by the extent of the width of the space 55 left open when the door is in its closed and locked position, and the time taken in opening and closing the door be accordingly less than if the door be moved across the entire width of the door opening, 60 Returning to the description of the interlock mechanism with the free end of the latch bar abutting against the side, 16, over the notch, 19; a further movement of the channel piece, 17, in the same direction last 65 above referred to, will serve to free the end

of the latch bar from that portion of the side, 16, over the notch, and allow the end of the bar to ride over the rounded surface of the block, 20, and rest in the angle or joint between the block and side, 18. In that 70 position, the bar locks the channel piece against being moved in a reversed or opposite direction, which position of latch bar and channel piece denotes the position of the door as being tight shut, closed or substantially so, across the entire width of the hatchway door opening, and locked in that position against being moved to open it. It will be reflected, therefore, that the present 75 interlock mechanism will care for either case of a door adapted to be shut tight closed across the entire width of the hatchway door opening and then be locked in that position by the free end of the latch bar 4 engaging the channel piece 17 in the angle between it 80 and the triangular shaped block 20 furthest from the base plate, which engagement will serve to lock the door when it is tight shut; against being opened in its tight shut position or adapted to be partially closed 85 across the width of the door opening, and then be locked in its partially closed position by the free end of the latch bar 4 engaging the channel piece 17 in the angle between it 90 and the block 20 nearest to the base plate. 95

Projecting from the channel piece is an ear, 21, in which is fixed a pin, 22. Freely straddling the pin is a fork, 23, formed in one end of an arm, 24 of a straight lever, 25, pivoted on a pin, 26, fixed in the base plate. In the end of the other arm, 27, of the lever is another fork, 28, with tine, 29, in a straight line with the lever, and another tine, 30, outwardly flared and shorter than its fellow tine, 29. The purpose of the 100 lever, 25, is to move the channel piece, 17, across the base plate, from over the free end of the latch bar, 4, by the closing movement of the door, the tine, 29, serving as a means to be engaged by a projection from the door, 105 as will be explained more fully later on. The projection from the door is shown in the case of the present interlock mechanism as a bar, 31, and is adapted to be rigidly fastened to the door, in a dependent position to 110 have its free end strike against the tine, 29, in the closing movement of the door. The side of the bar which strikes against the tine, 29, is straight throughout its 115 length; but the other side at the end is beveled, as at 32, forming of the end of the bar what may be generally termed a conical point. As the fork, 23 swings in the arc of a circle, and the bar, 31, moves in a horizontal straight line, it will be perceived that by 120 making the tine, 30, shorter than the tine, 29, more bearing surface is obtained between the bar and tine, 29, than could be obtained were the tines of equal length. By flaring the tine, 30 outwardly, wear is lessened between 125 130

the tine, 30; and the bar, 31, in their operation of separating from each other; but the gist of the matter of incline or bevel, 32, in connection with the flared tine, 30, is that 5 when the door, by the contact of the straight side of the bar, 31, against the tine, 29, turns the lever, 25, to its locked position, of the latch bar engaged with the channel piece, and the door reaches its closed position, the 10 door may rebound therefrom slightly, and in such event, there is room enough for the inclined or beveled point of the bar to move slightly in the space left between the bevel and the flare, by reason of the bevel and flare 15 of the tine, 30. A straight lever, 25, and straight bar, 31, are ordinarily used when the door is horizontally sliding; but where the door is vertically sliding, a bell-crank lever, 33, is resorted to, and the beveled 20 point of the bar is set at a right angle to the straight side of the bar, as indicated in the figures of the drawing. In the case of the single door, vertically opening, the flared tine, 30, and the bevel, 32, of the bar, 31, are 25 set in an upward direction, as shown in Figures 11 and 12; and in the case of a two-part, vertically opening door, one part to be moved upwards and the other part downwards, the bevel and flare directed downwards, as shown in Figures 13 and 14. As 30 the interlock mechanism is designed to be used for horizontally sliding doors which open either from the right hand or left hand side, simply by inverting the base plate, 1, 35 two bevel pieces, 6, have been provided, one on each side of the latch bar, 4, as has been stated, and two holes 34, in the base plate are provided, in either one of which the pin, 26, can be fixed on which to mount the lever, 25; but in the case of either right hand or 40 left hand opening door the straight side of the bar, 31, should be set to engage the straight tine, 29.

The description will now proceed to 45 describe the connection between the lock mechanism, already described, and adapted, to be secured to the floor landing, and the car control mechanism and the means whereby the latter is interlocked with the door 50 when the latter is in its open position. There is a bracket, 35, which is adapted to be fixed to the car beneath its platform, C, with perforated lugs, 36, in which is a pin, 37, on 55 which is pivoted a link, 38; with a perforation, 39, near its middle, and at its free end, is extended from one side thereof, is a fork, constituted of two lugs, 40, with inclined opposite side walls, forming a flared opening between them. On the other side of the link is a 60 roller, 41. The side, 18, of the channel piece has already been mentioned, but it is designed that the fork shall embrace the free edge of the side, 18, and one of its lugs, 40, bear against the inside of the side, 18, to prevent 65 the car control mechanism from being oper-

ated when the door is open (see for convenience, Figure 7), as will be presently described. On account of the fact that it is not always the case that the car stops level with the floor landing or remains level therewith, 70 the side, 18, is made of sufficient length to insure that it will invariably present a point of engagement therewith of the lug, 40, and its ends rounded to allow some flexibility of contact between the lug and the free ends of 75 the side at the beginning of their engagement.

Returning to the roller, 41, it will be explained that its function is to be moved by the movement of the car control mechanism 80 in stopping the car, against the latch bar, 4, in its extended position, to press it inward towards the base plate, 1, and unlatch its free end from its engagement with the channel piece, to allow the door to be opened from its closed position, in which it was locked by the latch bar. Because the car may not stop at the landing invariably level therewith or so remain therewith when stopped thereat, 85 the latch bar is widened, by means of wings, 90 42; and the tips, 43, are rounded to facilitate ease of engagement between them and the roller. In the perforation, 39, in the link, 38, is a pin, 44, pivotally securing thereto a coupling, 45, which is connected to a rod, 46, the other end of which is connected to one arm, 47, of a bell-crank lever, 48, fulcrumed on brackets, 49, adapted to be fixed to a car, beneath its platform, C, and the other arm, 50, adapted to be pivotally connected to a rod, 51, and the other end of that rod to be connected by a pin, 52, to the car switch lever, 53, and adapted to be moved by the movement of the car lever in the operation of controlling the car. 95 See Figures 9, 10, 11, 12, 13 and 14. The inertia of the movable parts of the interlock mechanism is so small that its addition to the inertia of the car control mechanism is hardly perceptible to the operator of the 100 car, especially so, when, as is usually the case, the car switch lever is provided with the conventional spring to return the lever to its centered or "off" position. But in order to take care of the inertia of the movable parts of the interlock mechanism, in the 105 operation of returning them to the position they are caused to assume when the door is fully opened, a tension spring, 54, may be employed with one of its ends fast to the arm, 47, of the bell-crank lever 48, and its other end fast to the car. It will be observed that, in the case of the car switch lever control mechanism, the spring, 53, is 110 relatively located so as to accelerate the roller, 41, in being moved to engage the latch bar, see Figures 9, 10, 11, 12, 13 and 14. Assuming that the car switch lever, 53, shown in the drawings, is provided with a 115 spring, it will be perceived that the spring 120

125 130

54 and the spring on the car switch may mutually aid each other in the movement of the lever to its centered or "off" position and the roller to its position of unlatching the latch 5 bar. As the car switch lever and roller are positively connected together, any movement of the lever serves to move the roller, and, therefore, in that sense, it may be properly said that the operation of both unlocking 10 and locking the latch is automatic when the interlocking mechanism is used with a car switch lever control mechanism. See Figures 9, 10, 11, 12, 13 and 14.

In the case of an elevator, with a hand 15 lever, 55, control mechanism, adapted to be swung over a quadrant, 56, for instance, as shown in Figures 15 and 16, with a vertically reciprocal catch, 57, on the lever, and notch, 58, in the center, of the quadrant, 20 adapted to receive the catch, when the lever is in its centered or "off" position, the end of the rod, 51, next to the car lever, is pivoted to one end of a link, 59, and the other end of the link pivoted to the catch, 57; but 25 the movement of the car lever will not move the roller, 41; however, a foot button rod, 60, is provided and vertically mounted in the car platform, C, with its end projected therethrough, and pivoted to the arm, 30 50, of the bell-crank lever 48. The spring, 54, is relatively located so as to tend to move the roller 41 out of the path of the latch bar, 4, and hold the button of the push rod normally above the floor of the platform. The 35 catch, 57, on the car lever, and the push rod, both being connected to the same arm, 50, of the bell-crank lever, they will be moved by stepping on the button, and the catch, 57, be pulled downwardly into the notch, 58, 40 and thereby lock the car lever against being operated at that time, and the roller be moved against the latch bar, 4, and unlock it, and consequently, the door. Upon stepping off of the button, it will be caused to 45 rise to its former position above the floor, and the catch, 57, also be moved out of the notch, 58, in the quadrant, and the car lever be unlocked; but the door be closed, and locked. The Figures 15 and 16 show the 50 parts just mentioned in the relative position they assume before the foot button is stepped on, and while the door is closed and locked.

In the case of an elevator controlled by a 55 hand wheel, a third arm, 61, is added to the bell-crank lever, 48, and the foot button push rod, 60, connected to the third arm, and the free end of a rod, 62, adapted to enter a notch, 63, in the hand wheel, 64, when moved upwardly by stepping on the foot button rod. In this case the rod, 62, locks the wheel, and the roller, 41, unlocks the latch bar, 4. In the Figures 17 and 18 the rod, 62, is shown out of the notch, the roller 60 swung clear of the path of the latch bar, and

the foot button above the floor of the car in position to be depressed by the foot, and cause the rod, 62, to move into the notch and the roller to move the latch bar to unlock it, and allow the door to be opened.

In the case of an elevator with hand rope car control mechanism, a lock mechanism is provided for the control hand rope, which may be of the usual conventional form or type of "rope lock"; for instance, that which is generally known in the art as the "Rochester" rope lock, which is adapted to be secured to the car platform by a bracket, 65, to which is affixed the "rope lock," comprised of a block or piece, 66, having a perforation therein, through which the control rope is passed, and a lock plate, 67, adapted to be moved across the perforation, to narrow it in effect, so that the usual stop balls on the rope cannot pass through the opening when so narrowed, when the car is stopped at a landing. The rope has the usual stop balls on it, as already implied, spaced apart from each other, so that when the car is stopped at a landing, the balls will be one on each side of the perforation in the block. The opening in the block is large enough for the balls to pass through it in the movement of the car. In the form of "rope-lock" shown in the drawings, the walls of the perforation are flared outwardly, to facilitate the movement of the rope and balls, in entering and leaving the perforation, and one end of the flat slide lock plate, 67, is made in the form of an open ended slot or fork of two prongs, joined together at their base in a half circle, corresponding to the circular outline of the perforation in the block, 66. When the plate is moved to the rope, the space or opening left between the plate and wall of the perforation is more or less elliptical, and smaller than the stop balls, and therefore they cannot be passed through the block, 66, at that time. On the tines or prongs of the flat plate, are expansion springs, 68, which tend to draw the plate towards the rope. The other end of the plate is connected to a link, 69, pivoted to an arm, 70, fast on one end of a shaft, 71, supported in bearings, 49. The shaft has an arm, 50, connected to the foot button, 60, and an arm, 47, connected by rod, 46, to the coupling, 45, on the link, 38, carrying the roller, 41, and a spring 53, between the arm 47 and the car platform. See Figures 19 and 20. While a particular form of "rope-lock" is disclosed, it will be understood that the adaptation of the interlock mechanism is not confined to it, but that it is expected that any person skilled in the art can adapt the interlock mechanism and a "rope-lock" of any other kind, generally speaking, to each other. In describing the construction of the interlock mechanism and its connection with

the car control mechanism, its principle and mode of operation also were more or less described; and therefore, it is thought that it is not desirable or necessary to add to the 5 length of the specification by consecutively describing its operation.

While the construction of the interlock mechanism has been shown, and its principle and mode of operation, described more or 10 less in detail, it will be understood that it is desired that the invention shall not be considered to be confined to its present embodiment, but shall include such mere changes in the number, design and relative arrangement 15 of parts as may be found to be still within the scope of the invention.

Having disclosed the invention, what is desired to be claimed is:

1. In the art of elevator hatchway door 20 mechanisms for locking the doors in closed position, the combination of a latch bar, adapted to be moved both vertically and horizontally the two being compounded into a resultant motion; and a lug, with an inclined 25 face, adapted, when the bar is being moved vertically, to direct the bar outwardly as well, to effect an engagement between it and the catch therefor.

2. In the art of elevator hatchway door 30 mechanisms for locking the doors in closed position, the combination of a latch bar, having a knuckle; a vertical pintle; an eye, in which the lower end of the pintle is held; the knuckle being hinged on the pintle, at a 35 distance above the eye, and adapted to fall along the pintle until it rests on the eye; and a downwardly inclined lug, in contact with the bar, adapted to force the bar outwardly in its falling movement, and an 40 emergency spring, adapted to apply its force to the bar in its movement to engage a catch or keeper therefor.

3. In the art of elevator hatchway door 45 mechanisms for locking the doors in closed position, the combination of a longitudinal latch bar, and a catch or keeper therefor; the latter and the end of the bar adapted to engage each other and lock the door in closed position, and the keeper having a 50 notch in it, through which the end of the bar may protrude when the said parts are disengaged from each other and the door is in an open position.

4. In the art of elevator hatchway door 55 mechanisms for locking the doors in closed position, a catch or keeper for the latch bar, comprised of an angle piece of two sides, and a part projected from the angle between the sides; the two sides and said part adapted to be abutted by the end of the latch bar 60 to lock the door in positions against being opened.

5. In the art of elevator hatchway door 65 mechanisms for locking the doors in closed position, the combination of the locking

mechanism, comprising a locking member, having a pivoted fork, with two prongs, one shorter than the other, and flared; a bearing member, adapted to be connected to the door, and moved thereby rectilinearly, to engage 70 the prongs in the operation of closing and locking the door and opening and unlocking the door.

6. In the art of locking elevator hatchway doors in closed position, the combination of 75 a locking mechanism, adapted to lock the door in closed position, comprising a member having an enlarged opening, and means, adapted to be connected between the locking mechanism and the door, comprising a 80 bearing adapted to be entered into the said opening, and bear against one wall thereof in the movement of the door in the operation of moving it to a closed position, but leave a space between the said bearing and 85 the opposite wall of the said opening, whereby, if the door rebound from its closed position in the operation of closing it, its rebound movement will not be transmitted to the said locking member, yet, nevertheless, 90 the latter will prevent the door from being further opened.

7. In the art of locking elevator hatchway doors in closed position, the combination of 95 a locking mechanism, comprising a lever, with one straight arm, with a two-tined fork in its free end, one of the tines being straight with the arm, and the other flared; and a bar, connected to the door, and adapted to be entered between the tines, the bar having 100 one straight side to bear against the straight tine, in the movement of the door in closing, and a beveled side, opposite the flare of the tine, with a space between the bevel and flare, whereby if the door rebound, its rebound 105 movement will not be transmitted to the locking member, yet, nevertheless, prevent the door from being further opened.

8. In the art of elevator hatchway door 110 mechanisms for locking the doors in closed position, the combination of the locking mechanism, comprising a locking member, having an opening therein, and a bearing, adapted to be connected to the door, and by the closing movement of the door to be entered into the said opening, and to move the locking member into position to lock the door when it has reached its closed position against being opened, the fit between the said opening and bearing member being loose, so 115 as to allow lost motion of the bearing member relatively to the locking member in the rebound movement of the door.

9. In the art of elevator hatchway door 125 and car control mechanisms for locking the door in closed position and the car control mechanism when the door is open, the combination of a latch bar, and keeper therefor, adapted to be engaged with each other to lock the door in closed position, and a lug, 130

connected to the car control mechanism, adapted to be held by the keeper when the car is at a landing and the door is in an open position, to prevent operation of the car control mechanism at that time.

10. In an elevator car hatchway door and car control interlock mechanism, adapted to interlock the car control mechanism with a hatchway door when the car is at a landing and the door then is in an open position, the combination of the control mechanism, a pair of lugs, spaced apart from each other, and adapted for use with either a right or left hand opening door, and connected to the control mechanism; and a part or element at the landing, and adapted to bear against one of the lugs, and prevent the control mechanism from being operated when the car is at a landing and the door in an open position.

11. In the art of elevator interlock mechanisms, adapted for use with hand rope car control mechanism, the combination of a rope-lock mechanism, to be carried by the car, and having a vertical perforation, adapted to receive the rope and stop balls; and a plate, operable to narrow in effect the perforation, to prevent the stop balls from being passed therethrough; a pedal, adapted to be mounted on the car and depressed to operate the plate to narrow in effect the perforation; and mechanism adapted to be fixed to a landing, and lock the plate against being opened when the car is at a landing and the hatchway door is in its open position; and connections between the pedal, the plate and the locking mechanism, whereby, by depressing the pedal, the plate is operated to lock the rope between the stop balls, and unlock the latch bar of the door-locking mechanism, and, upon the door being opened, the door locking mechanism to lock the plate against being operated to release the stop balls until and unless the door be first closed.

12. In an elevator, the combination of the car, car controller lever, and hatchway landing door, of means at the landing floor to effect the locking of the said door, a pedal, and mechanism on the car, adapted to be operated by the said pedal, said mechanism comprising a part on the lever, adapted to lock the lever in its neutral position and another part, adapted to be operated by the pedal to unlock the said door-locking means, and another part to engage the door locking means to preserve the locked condition of the lever.

13. In an elevator, the combination of the

car, car controlling lever, and a landing door, and a part or projection affixed to the door, mechanism at the landing, to effect the locking of the door, said mechanism embracing a part, adapted to be reciprocated, positively in both directions, as the result of an engagement between it and the said projection on the door, and mechanism on the car adapted to be operated by the movement of the car controller lever, comprising a part adapted to lock the lever in its neutral position and a part adapted to unlock the door locking mechanism, and become engaged with the said reciprocable part thereof, to continue the locked condition of the door locking mechanism.

14. In an elevator hatchway door locking system, means adapted to lock the door when closed or in a predetermined partially closed position, comprising a latch, a movable keeper therefor, means between the door and keeper, whereby the door in movement to a closed or said partially closed position effects a movement of the keeper, the latter characterized by having detents adapted to be engaged by the latch, the location of the detents relatively to each other corresponding in effect to the closed and said partially closed positions of the door, and to check or prevent the operation of opening the door when it is in its closed position and further opening the door when it is in its said partially closed position.

15. In an elevator safety system, wherein the hatchway door and the car control mechanism are adapted to be interlocked with each other when the car is at a desired landing, the combination of means adapted to lock the door when closed, a movable keeper therefor, means between the door and keeper whereby the door in its movement to a closed or said partially closed position effects a movement of the keeper, the latter provided with detents adapted to be engaged by the latch, the detents being relatively located to each other to correspond in effect to the closed and said partially closed positions of the door, and to lock the door against being opened when it is in its closed or said partially closed positions, and mechanism whereby the latch can be disengaged from the detents and the door be thereby unlocked, and, upon opening it from its closed positions, the car control mechanism be prevented from being operated.

In testimony whereof, I have signed my name to this specification.

THOMAS H. STRALEY.
